CLAIM

The ornamental design for a material having edging, as shown and described.

DESCRIPTION

FIG. 1 is a perspective view of a material having edging showing our new design;

FIG. 2 is a cross-sectional perspective view of the material having edging, taken along lines 2-2 in FIG. 1;

FIG. 3 is a top plan view of the material having edging shown in FIG. 1;

FIG. 4 is a front elevation view of the material having edging shown in FIG. 1;

FIG. 5 is a rear elevation view of the material having edging shown in FIG. 1;

FIG. 6 is a right side plan view of the material having edging shown in FIG. 1; and,

FIG. 7 is a left side plan view of the material having edging shown in FIG. 1.

The evenly spaced broken lines in FIGS. 1 through 7 represent portions of the material having edging and form no part of the claimed design. The material having edging is shown with a symbolic break in its length and width. The appearance of any portion of the material having edging between the break lines forms no part of the claimed design.
